UNITED STATES PATENT OFFICE.

LEWIS C. NORTON, OF CHICAGO, ILLINOIS, ASSIGNOR TO NORTON DOOR CHECK COMPANY, OF CHICAGO, ILLINOIS, A CORPORATION OF WEST VIRGINIA.

DOOR OPERATING AND LOCKING MECHANISM.

1,117,694.

Specification of Letters Patent.

Patented Nov. 17, 1914.

Application filed May 23, 1914. Serial No. 840,637.

To all whom it may concern:

Be it known that I, LEWIS C. NORTON, a citizen of the United States, residing at Chicago, county of Cook, State of Illinois, have invented an Improvement in Door Operating and Locking Mechanism, of which the following description, in connection with the accompanying drawing, is a specification, like characters on the drawing 10 representing like parts.

This invention relates to operating mechanism for sliding doors and particularly to door-operating devices of that nature which include a toggle lever arrangement comprising two members pivotally connected together and pivoted to the door and a fixed abutment, respectively.

The objects of the invention are to provide a mechanism of this nature with novel 20 means for locking the toggle lever device when the door is closed and for unlocking and breaking said toggle lever device when the door is to be opened.

In accordance with my invention I provide the two toggle lever members with portions that overlap each other when the door is closed and also provide means having an interlocking engagement with the overlapping portions to lock them against relative 30 movement. In the preferred embodiment of my invention this means is associated with the handle by which the door is opened and the parts are so arranged that when the operator moves the handle the first movement of the handle will unlock the toggle members while further movement of the handle will break the toggle and open the door.

In order to give a proper understanding 40 of my invention I have illustrated in the drawings a selected embodiment thereof which will now be described after which the novel features will be pointed out in the appended claims.

45 Figure 1 of the drawings is a view showing my invention as applied to a two-section door; Fig. 2 is a top plan view of a portion of the toggle lever mechanism; Fig. 3 is a perspective view of the overlapping portion of the toggle levers and the means for locking them in their overlapping relation.

While I have herein illustrated my invention as applied to a sectional door I desire to state at the outset that the invention is 55 not limited to a sectional door, but can be

applied to a toggle-lever door-operating mechanism adapted to operate a single door only. My invention can be applied to any sliding door, but has special advantages when applied to the sliding doors of elevators and elevator wells.

In the drawings I have shown at 1 and 2 two sliding door sections which are adapted to be moved from the full line position Fig. 1 in which the door is closed to the dotted 65 line position in which the door is open.

The means herein shown for operating the doors comprises a toggle-lever device made in three sections 3, 4 and 5, respectively. The section 3 is pivoted at its outer end to 70 the door section 1, as shown at 6, and at its other end it is pivoted to the section 4 at 7. The intermediate section 4 is pivoted to the rear edge of the door section 2, as shown at 8, and at its outer end is pivoted to the section 5, as at 9. The section 5 is pivotally 75 connected to a fixed abutment, as at 10, and in the case of an elevator door this abutment would be the walls of the elevator well. The construction of this toggle-lever arrangement is such that when the doors are closed the sections 3, 4 and 5 all stand in alignment with each other, as shown in full lines Fig. 1, thus locking the doors closed. When the doors are opened the section 3 and the 80 end of the section 4 to which it is pivoted move downwardly, while the opposite end of the section 4 and the section 5 move upwardly into the dotted line positions Fig. 1. If desired, I may associate with my toggle-lever device a combined door closer and 85 check shown at 11, as is commonly done in elevator door-operating devices, such door closer and check being in the form of a dash-pot arrangement having a door-closing 90 spring therein. This device 11 operates automatically to close the door and to check the closing movement thereof.

My invention aims to provide a novel device which is associated with the toggle-lever door-closing mechanism by which the toggle-lever is locked when the door is closed, which means also constitute the handle by which the toggle-lever is operated to open the door. The two members 3 and 4 of the toggle-lever device are arranged to present portions that overlap each other, this being herein provided for by extending the sections 4 beyond the pivot 7 to provide a portion 12 which overlaps the sec- 105 110

tion 3. I have herein shown the section 4 as made up of two bars between which the ends of the sections 3 and 5 are received. The overlapping portions of the sections 3 and 12 5 are provided with notches 13 to receive a locking member 14 which when in operative position locks the sections 3 and 4 in their alined position and prevents the toggle lever from breaking. This locking member 10 14 is herein shown as associated with a handle 15 by which the door can be operated. This handle may conveniently be pivoted to the section 4, as shown at 16, and it is provided with automatically-operative 15 means which tend normally to throw the locking portion 14 into locking position. Such automatically-operative means might be a spring or a weight, one being equivalent to the other. Where such means is in 20 the form of a weight I propose to provide the handle 15 with an extension 17 which is received between the two parts of the section 4.

The operation of the device will be readily understood from the foregoing. When the door is closed the parts are in the full line position Fig. 1 with the locking member 14 occupying the alined notches 13 in the sections 3 and 4, respectively, and when the 25 parts are in this position not only is the door locked because the sections 3, 4 and 5 are in alinement, but the sections of the toggle lever are locked from movement relative to each other and, therefore, the toggle 30 lever cannot be broken merely by pressure applied vertically to the sections 3 and 4. In order to open the door the operator grasps the handle 15 and draws downwardly thereon, this movement operating first to swing 35 the handle into the dotted line position Fig. 1 and remove the locking portion 14 from the notches 13. A stop pin 18 carried by the section 4 may be used if desired to limit the swinging movement of the handle 15 relative 40 to the section 4. When the handle 15 has been brought into the dotted line position Fig. 1 and the toggle lever sections are unlocked then further downward pressure on the handle 15 will break the toggle lever 45 and open the door as will be obvious. The operation of unlocking the toggle lever and then opening the door involves, therefore, merely a steady downward and backward pull on the handle 15, the initial movement 50 of the handle unlocking the toggle lever and the further movement breaking the toggle and opening the door. When the opened door is released the door closer and check 55 will operate to close the door automatically, and when the door has been closed the weight 17 or other automatically-operated 60 means will automatically cause the locking portion 14 to enter the notches 13 and thus lock the toggle lever in the position shown 65 in Fig. 1.

While I have herein shown the invention as applied to a sectional door, yet it will be obvious that it could be equally well applied to a single section door in which latter case the pivotal point 8 would be on a fixed abut- 70 ment instead of on a moving door section. The operation of the handle 15 and locking member 14 would not be affected, however, by such change.

While I have illustrated a selected embodiment of my invention, I do not wish to be limited to the constructional features shown.

I claim:

1. In a door-operating device, the combination with a sliding door, of a toggle-lever door-operating device comprising two members pivotally connected together, one of which is pivotally connected to the door, said members having portions that overlap 80 each other when the door is closed, and means having interlocking engagement with said overlapping portions to lock them from movement relative to each other.

2. In a door-operating device, the combination with a sliding door, of a toggle-lever door-operating device comprising two members pivotally connected together, one of which is pivotally connected to the door, said members having portions that overlap 90 each other when the door is closed, and a handle for opening the door co-operatively connected to one of said members and provided with means having interlocking engagement with said overlapping portions 95 when the door is closed to lock the toggle-lever sections from movement relative to each other.

3. In a door-operating device, the combination with a sliding door, of a toggle-lever 105 door-operating device comprising two members pivotally connected together, one of which is pivotally connected to the door, said members having portions that overlap each other when the door is closed, and a 110 handle pivoted to one of said toggle-lever members and having means to interlock with the overlapping portions of said members to lock them in their alined position when the door is closed.

4. In a door-operating device, the combination with a sliding door, of a toggle-lever door-operating mechanism comprising two members pivotally connected together, one of which members is pivotally connected to 120 the door, said members having portions which overlap each other, and said overlapping portions being provided with notches which are in alinement when the door is closed, a handle pivotally mounted to one 125 of said members and provided with a locking portion to enter said notches when in alinement and lock the toggle-lever members from relative movement, movement of the handle operating first to unlock the toggle- 130

lever members and then to break the toggle and open the door.

5. In a door-operating device, the combination with a sliding door, of a toggle-lever door-operating mechanism comprising two members pivotally connected together, one of which members is pivotally connected to the door, said members having portions which overlap each other and said overlapping portions being provided with notches which are in alinement when the door is closed, a handle pivotally mounted to one of said members and provided with a locking portion to enter said notches when in 10 alinement and lock the toggle-lever members 15
- from relative movement, movement of the handle operating first to unlock the toggle-lever members and then to break the toggle and open the door, and automatically-operative means acting on said handle to bring 20 the locking portion into the alined notches when the door is closed.

In testimony whereof, I have signed my name to this specification, in the presence of two subscribing witnesses.

LEWIS C. NORTON.
